Primary Examiner — Kevin K Rudzinski*Assistant Examiner* — Evans David Delesline(74) *Attorney, Agent, or Firm* — Polsinelli PC(57) **CLAIM**

The ornamental design for a coin display wristband, as shown and described.

DESCRIPTION

FIG. 1 is a top, front and right perspective view of the coin display wristband showing our new design.

FIG. 2 is a front elevation view thereof.

FIG. 3 is a bottom perspective view thereof.

FIG. 4 is a back elevation view thereof.

FIG. 5 is a top plan view thereof.

FIG. 6 is a bottom plan view thereof.

FIG. 7 is a right-side view thereof.

FIG. 8 is another top, front, and right perspective view thereof having a coin secured within the centerpiece; and, FIG. 9 is another top plan view thereof having the coin secured within the centerpiece.

The coin shown in broken lines shows environment and forms no part of the claimed design.

1 Claim, 4 Drawing Sheets(56)
